UNITED STATES PATENT OFFICE.

ORVILLE L. PARMENTER, OF CINCINNATI, OHIO, ASSIGNOR, BY MESNE ASSIGNMENTS, TO JANE E. KEITHLY, OF SAME PLACE.

MACHINE FOR THE PRINTING OF CIGAR-TAGS.

SPECIFICATION forming part of Letters Patent No. 367,117, dated July 26, 1887.

Application filed November 2, 1882. Serial No. 75,778. (No model.)

To all whom it may concern:

Be it known that I, ORVILLE L. PARMENTER, of the city of Cincinnati, in the county of Hamilton and State of Ohio, have invented certain new and useful Improvements in Machines for the Printing of Cigar-Tags, of which the following is a specification.

Referring to the drawings, forming part of this specification, Figure 1 represents a blank sheet of paper mounted on a temporary backing of card or straw board preparatory to receiving the printing of the tags. Fig. 2 represents one of these sheets after being printed, the lettering being shown on only two vertical rows of tags, but the perforated division-lines between the various vertical rows being shown throughout the sheet. Fig. 3 is a view of one edge of Fig. 2, showing the manner of connecting the sheet of paper to the temporary backing. Fig. 4 represents several of these sheets removed from the temporary backing and secured preparatory to cutting into longitudinal strips. Fig. 5 represents one of the printed sheets, showing how it is cut into longitudinal strips. Figs. 6 to 14, inclusive, represent the mechanism for printing the sheets, Fig. 9 being a side view of what is known as the "Model Press," upon which I make no claim, but merely show to better illustrate my invention. Fig. 10 is a front view of the supporting and guide plate which I attach to the press to properly guide the sheet being printed. Fig. 6 is a back view of said plate attached to the machine. Fig. 14 represents the sheet being printed in position in the guide-plate. Figs. 7, 8, 11, 12, and 13 are detail views of various parts of the guide-plate.

Any suitable form of press may be employed, and my improved guide, &c., connected thereto. In the present instance, for the purposes of illustration, I have shown the guide and plate applied to a small press known as the "Model Press."

A is the supporting-plate, which is connected at one end to the platen *a* of the press by means of screws or other suitable fastenings, *a'*, the other end of said plate projecting from the side of the press, as shown in Fig. 6.

The portion or head *B* of the plate *A* which is in contact with the platen of the press is wider than the extended portion *b*, and is pro-

vided with an opening, *b'*, the purpose of which is to allow the paper being printed to come in contact with the mat of flexible material on the platen. A guideway, *c*, is formed at or near the lower edge of plate *A*, and is preferably formed as follows: The lower edge of the plate *A* is turned up, forming a flange, *C*, between which and the plate *A* is thus formed the guideway *c*, extending from end to end of the plate.

At or near the upper side of the head *B* of the plate there is located a guide, *D*, preferably adjustable by suitable means, and the preferable mode of connecting this guide is by means of screws *d*, which engage in slots *d'* in the upper edge of the guide, by which connection the guide may be raised and lowered to adjust it to the width of the paper to be printed. This guide *D* has a downwardly-extending flange, *E*, between which and the plate *A* a channel or guideway, *e*, is left. This flange *E* is preferably cut away at *e'*, so that it will not interfere with the type when the platen is caused to approach the latter, and so that a greater amount of surface of the paper can be printed than would be the case were the flange not open at *e'*.

The upper edge of the extension *b* of the plate *A* is provided with a serrated gage, *F*, and the latter is preferably made separate from the plate *A* and secured to the latter as follows: The plate *A* is made with a flange, *f*, extending backward at right angles to the plate, and upon this flange is secured the gage *F* by means of screws or bolts *f'*, the length of the teeth *g* of said gage being equal to the length of each tag to be printed.

As the platen *a* usually moves, and the guide-plates *A* are therefore usually attached to the platen, it becomes desirable that the plate *A* should be light in order not to interfere with the rapid movements of the platen. The plate *A* is therefore made thin, and, to give the greater rigidity, a brace-rod, *G*, is connected at one end to some part of the press, the other end of the rod being connected to the outer end of the plate *A*, or, as shown in Figs. 6 and 10, to the end of the gage *F* on top of said plate, the lower portion of the plate *A* preferably resting against the rod *G*.

The paper upon which the tags are to be

printed is first gummed and then cut into sheets H, the width of said sheets being usually governed by the size of the press. These sheets H are then stuck at each end to a temporary 5 backing, I, of card straw-board or other suitable material, as shown in Fig. 3. This backing is preferably a little wider than the sheet H, and one end, h, of said backing extends beyond the end of the sheet, as shown. The 10 sheets are each connected to a backing in order that they may be the better held in shape and carried through the press and to afford a true surface or mat for the sheet being printed. The sheet H, having been secured to the backing I, is placed between the flanges C and E, the edges of the backing I resting in the channels or guideways c and e. The end h of the 15 backing I is first placed between these flanges and pushed through until its end comes in contact with the first tooth g of the gage, which will bring the end of the sheet H into a position to receive the impress of the type when the platen is advanced. At the first advance of the platen the first vertical row of tags is 20 printed and also the first line of perforations between it and the next row. When the platen has been retracted, the sheet and the backing are drawn through the flanges C and E until the end of the backing, by being slightly 25 depressed, will rest against the second tooth g of the gage F, and these teeth being of the same length as the length of the tags, at each successive advancement of the platen one tooth of the gage, the sheet H and its backing being 30 drawn through each time the length of one of the teeth g, the vertical rows of tags are evenly 35 printed and perforated, one row being printed each time until the sheet is entirely printed. The flanges C and D hold the backing H and 40 the sheets thereto connected in close contact with the platen of the press, so that an even and true surface is presented to the type.

If it is desired to print more than one vertical row of tags at one impression, the type 45 and perforators may be arranged for the desired number of vertical rows and the sheet and backing must then be drawn through each time to the desired tooth of the gage. For instance, if two vertical rows are printed at once, 50 one tooth of the gage must be skipped each time, and if three rows, then two teeth must be skipped each time, and so on. By this it will be seen that any desired number of vertical rows of tags may be printed at one impression, according to the capacity of the 55 press. When a number of these sheets have been printed, they are removed from their respective backings I, and the ends of these printed sheets are then stuck together, as 60 shown in Fig. 4, care being taken that the edges of the sheets are even. When the desired number of sheets have been thus secured together, they are cut longitudinally, as shown by the line x, Fig. 5, the tags being thus 65 separated into longitudinal rows, several of these

rows being connected at each end, forming a bundle, in which form the tags are furnished to the cigar-manufacturer, and in this form the tags will keep their shape and be convenient for handling. When the tags are to be used, 70 one of these rows is detached from the bundle, and as the line of separation between the tags is perforated one tag at a time is easily stuck onto a cigar and detached from the row. The backings I, from which the printed sheets 75 are detached, may be used a number of times, and are not therefore wasted. If desired, however, the sheet may be cut into longitudinal rows before being detached from the backing, and thus the backing be cut too, and each row will 80 then be provided with a backing, which will prevent the various rows, when necessity arises for putting same in a damp or moist place, from sticking together when done up in bundles. Tags are, within certain limits, made of different lengths, to suit the figure or name printed thereon, and also to suit the taste of the parties interested in their production. In order to enable the printing of these tags to be conveniently carried on, I provide for each different length of tag a gage, F, having teeth whose interspaces are each of the length, or a multiple of the length, of the tag to be printed. Should the gage on the press not have teeth with the right interspaces, I remove the said gage and 90 then substitute therefor on the plate A a new gage having teeth with the correct interspaces. Thus the plate A is adapted to receive interchangeable gages. 95

In certain instances--as, for example, where the tags are oval or round--the straight perforator is not used, but the tags are usually cut out by dies after being printed.

Having thus described my invention, what I claim as new, and desire to secure by Letters Patent, is as follows:

1. The guide and supporting-plate A, secured at one end to the platen of a printing-press and provided with guides C and D, and the gage F, for regulating the length of the tags being printed, substantially as and for the purposes specified.

2. The plate A, consisting of a head, B, and extension b, the lower edge of said plate being provided with a channel, c, and the upper part of the head having attached thereto a guide, D, forming a channel, e, and the upper edge of the extension b having attached thereto a serrated gage, F, substantially as and for the purposes specified.

3. The guide and supporting-plate A, formed substantially as described, and provided with opening b' and secured at one end to the platen of the press, and the supporting brace-rod G, substantially as and for the purposes specified.

ORVILLE L. PARMENTER.
